MOUTHPIECE FOR CAP MAGAZINES

Francis C. Rodman, Garden City, N. Y., assignor to American Seal-Kap Corporation of Delaware, Wilmington, Del., a corporation of Delaware

Application August 12, 1952, Serial No. 303,909

3 Claims. (Cl. 226—88.1)

This invention relates to capping machines of the general type shown in the Mackin and Goodwin Patent No. 2,563,654 dated August 7, 1951, which are adapted to dispense and apply to milk bottles preformed caps having a central diaphragm adapted to form a closure for the milk bottle and a depending flared skirt which is adapted to be constricted and sealed around the neck of the bottle, and has for an object to provide improved dispensing means to permit the caps to be removed one by one from a stack in the cap magazine.

Another object is to provide a mouth ring for the cap magazine which is adapted to conform automatically to different sizes of cap skirts.

Another object is to provide a mouth ring which is extensible to permit the passage of an oversize cap skirt.

Various other objects and advantages will be apparent as the nature of the invention is more fully disclosed.

The machine in general includes picker mechanism for picking individual caps successively from a stack of nested caps and feeding the picked caps to a bottle capping station. The picker mechanism withdraws the caps one at a time through a mouth ring at the end of the cap magazine. The mouth ring has a lip opening which is somewhat smaller in diameter than the largest diameter of the cap skirt and serves to restrain and hold the caps in the magazine. It is of a size however to permit a skirt to pass when the foremost cap is withdrawn by the picker mechanism.

In accordance with the present invention the mouth ring is made in two sections, at least one of which is mounted for movement in a direction to enlarge the lip opening. This movement is restricted by suitable means, such as springs or weights so that the ring is normally maintained in a given position with respect to the caps which are to be passed therethrough. The movable mounting for the ring however permits it to adjust itself automatically so as to accommodate irregularities in the sizes of the cap skirts. This prevents the caps with the larger skirts from becoming stuck and not feeding properly and also prevents a plurality of caps with smaller skirts from feeding at the same time.

The nature of the invention will be better understood by referring to the following detailed description taken in connection with the accompanying drawings in which a specific embodiment has been set forth for purposes of illustration.

In the drawings:

Fig. 1 is a partial side elevation with parts in section of the lower end of the cap magazine showing the relationship of the mouth ring and the picker mechanism;

Fig. 2 is a transverse section taken on the line 2—2 of Fig. 1;

Fig. 3 is an axial section through a portion of the picker mechanism and magazine on a larger scale;

Fig. 4 is a transverse section of the mouth ring taken on the line 4—4 of Fig. 5, and

Fig. 5 is an axial section taken on the line 5—5 of Fig. 4.

Referring to the drawings more in detail the invention is shown as applied to a portion of a capping machine of the general type shown in the Mackin et al. patent above mentioned and only so much thereof is set forth herein as is necessary to an understanding of the invention.

Fig. 1 shows the lower end of a cap magazine 10 containing a stack of caps 11 each of which has a central diaphragm 12, a pouring rim housing 13 and a fluted flaring skirt 14 which may or

may not contain an adhesive depending upon the type of cap involved.

A suction picker mechanism is generally indicated as comprising a suction head 20 which is adapted to be reciprocated and to engage the pouring rim housing 13 and the central diaphragm 12 of the caps and is mounted on a plunger 21 which is actuated by a suction controlled piston in a cylinder 22, the details of which are not involved in the present invention.

The mouth ring, in accordance with the present invention, comprises a lower section 30 and an upper section 31 having arcuate lips or flanges 32 and 33 respectively which engage the cap skirts at opposite sides for holding the lowermost cap in the magazine. The flanges 32 and 33 are positioned at the sides of the caps, leaving openings 35 and 36 at the bottom and top respectively. The openings 35 and 36 prevent the skirts from being too tightly gripped by the flanges 32 and

33 and also permit a slight variation in size of cap skirts without affecting the normal operation of the picker mechanism. The flanges are provided with conical inner surfaces 37 as shown in Fig. 3 which are disposed at an angle to conform as closely as possible to the average angle of flare of the cap skirts that are to be conveyed therethrough.

The lower portion 30 of the mouth ring is provided with ears 40 which are disposed over a sleeve 41 carried by a post 42 which is held in a

support 43 attached to the lower flange 44 of the cap magazine by means of bolts 45. The upper portion 31 of the mouth ring is provided with ears 50 having bores 51 which fit loosely over the sleeve 41 so that the ears 50 are free to slide or pivot thereon. Springs 52 disposed around the sleeve 41 between cap nuts 53 and ears 50 serve to resist movement of the upper portion of the mouth ring and tend to restore the same to its original position when the ring has been shifted in response to the passage of an oversize cap skirt.

It is obvious that if the ring is made sufficiently heavy the springs 52 may be omitted or in certain instances additional spring means may be provided to maintain the ring in its normal position. In certain instances, however, the weight of the ring member may be such as to unduly retard the pivotal motion of the member about the sleeve 41. In that case weights as indicated at 55 may be disposed on the ears 50 in a position to counterbalance at least in part the weight of the movable ring member. The ring member may of course be hinged by other means and the springs which oppose the rocking or pivotal motion may be otherwise disposed in accordance with the effect desired and in accordance with the weight of the movable member.

In the operation of this device the upper section 31 of the mouth ring normally remains in fixed position as the caps are pulled through the opening in the lips 32 and 33 by the picker mechanism. However, in the event of the passage of an over size skirt the upper section 31 is raised slightly against the force of the springs 52 by pivoting on the sleeves 41 so as to allow the skirt to pass. The weight of the movable portion 31 and the force of the springs 52 is of course so selected with respect to the action of the suction head that the cap skirt is allowed to pass through the ring opening without stripping the cap from the suction head. In this way a substantially uniform feed is obtained regardless of the minor variations in sizes of cap skirts which occur in normal operations.

The size of the bore 51 in the ears 50 is such that the upper section 31 rocks or pivots about the sleeve 41 instead of sliding along said sleeve to any appreciable extent. The force required to move the section 31 is such that the member is adapted to move in response to the passage of a cap skirt without stripping the cap from the picker mechanism.

A specific embodiment has been shown for purposes of illustration. It is to be understood however that changes and modifications may be made therein and that the invention may be ap-

plied to various uses as will be apparent to a person skilled in the art.

What is claimed is:

1. In a bottle capping machine, a magazine adapted to receive a stack of nested hood caps having a central diaphragm portion and rearwardly flaring skirts, a mouth ring disposed at the forward end of said magazine and having a flange engaging the skirt of the foremost cap to retain the stack in said magazine and having an opening through which said cap is withdrawn, said mouth ring comprising at least two sections, a pin supporting said mouth ring, one of said sections having an ear loosely mounted on said pin to permit sliding and rocking movement thereof with respect to said pin.

2. In a bottle capping machine, a magazine adapted to receive a stack of nested hood caps having a central diaphragm portion and rearwardly flaring skirts, a mouth ring disposed at the forward end of said magazine and having a flange engaging the skirt of the foremost cap to retain the stack in said magazine and having an opening through which said cap is withdrawn, said mouth ring comprising at least two sections, a pin supporting said mouth ring, one of said sections having an ear loosely mounted on said pin to permit sliding and rocking movement thereof with respect to said pin.

30 carried by said pin to oppose such movement.

3. In a bottle capping machine, a magazine adapted to receive a stack of nested hood caps having a central diaphragm portion and rearwardly flaring skirts, a mouth ring disposed at the forward end of said magazine, said ring having a pair of oppositely disposed arcuate flanges to engage opposite sides of the skirt of the foremost cap to retain the stack in said magazine, said flanges being spaced apart at the top and bottom to leave openings through which the skirts pass without contact, said ring being split horizontally into top and bottom sections, said bottom section being fixed to said magazine, ears projecting axially of the magazine from said top section, and supporting pins loosely carrying said ears to permit pivotal movement of said top section in response to passage of a cap skirt.
